Durafer Incorporated, Newark, N. J., a corpora-
tion of Delaware

Application September 9, 1933, Serial No. 688,831

11 Claims. (Cl. 22—65)

This invention relates to centrifugal cast articles such as brake drums and the process and apparatus relative to the centrifugal casting thereof, and more particularly to centrifugal casting about a vertical axis.

5 Cast iron has long been recognized as an excellent friction brake material, but due to its inherent weaknesses, lack of strength, internal stresses, brittleness, etc., its use for brake drums has not usually been found practical apart from some form of metallic supporting structure. These composite structures due to severe temperature changes and conditions arising in brake drums, producing unequal expansion and contraction, are not free from difficulties. This invention is, therefore, particularly directed to an improved composite drum and the method and apparatus adapted to produce the same.

Accordingly an object of this invention is to provide an improved brake drum having a shell and a centrifugally cast liner so arranged that separation between the welded liner and shell is mechanically substantially impossible.

20 Another object of the invention is to provide a brake drum having a shell and cast liner, the shell being deformed along an edge and irremovably interlocked with the cast liner.

25 A further object of the invention is to provide in a brake drum, a shell having a bell mouthed edge portion and a cast lining provided with a flange encompassing the bell mouth so as to be rigidly secured to the shell.

30 A still further object of the invention is to provide a brake drum structure which may be of such a design as to properly conduct and distribute the heat incident to casting a liner therein.

35 Yet another object of the invention is to provide a centrifugal casting machine adapted to produce the novel drum structure and employ the same in establishing a substantially permanent mold casting machine.

40 Still another object of the invention is to provide an annular trough means for receiving molten metal, the trough being so supported and 45 constituted as to be free from overheating from the adjacent molds.

45 A still further object of the invention is to provide in a centrifugal casting machine a rotatable annular trough adapted to measure quantities of molten metal when stationary and discharge molten metal therefrom only after a predetermined substantially full speed is attained.

50 Another object of the invention is to provide novel means for supporting a diaphragm member within the centrifugal casting apparatus so that quick securing and release is obtained to the end that the casting may be quickly removed from the machine and cooled in atmosphere or other suitable means.

55 60 A further object of the invention is to make a

casting welded to a shell without the necessity of preheating the shell.

A still further object of the invention is to cast molten iron into a diaphragm shell at room temperatures without distortion of the diaphragm of the shell.

5 Further objects of the invention and other novel features will appear more fully hereinafter from the following detailed description when taken in conjunction with the accompanying drawings. It is expressly understood, however, that the drawings are employed for purposes of illustration only and are not designed as a definition of the limits of the invention, reference being had for this purpose to the appended claims.

10 In the drawings wherein similar reference characters refer to similar parts throughout the several views:

15 Fig. 1 is a front elevation of the casting machine with the mold and associated elements shown in section;

20 Fig. 2 is an enlarged section of a portion of Fig. 1 diagrammatically illustrating the flow of molten metal;

25 Fig. 3 is a section through a portion of a modified mold and finished brake drum;

30 Fig. 4 is a front elevation similar to Fig. 1 illustrative of the manner of preparing the machine for operation, and

35 Fig. 5 is a section through the upper part of the machine of Fig. 4 and illustrative of an improved form of holding means for the brake drum diaphragm.

40 Referring to the drawings and more particularly to Fig. 1 therein, the casting machine comprises a foundation 10, frame 12 for supporting the upper half of the casting machine and a motor 14 for supporting the lower part thereof. The motor is provided with a shaft 16 carrying thereon a mold supporting spider 18 having an annular rim portion 20 flanged or shouldered at 22 to receive and center a mold section 24.

45 Pins 26 extending parallel to the axis and adapted to extend into the mold cavity are retained by springs 28 and shoulders 30 so that their inner ends 32 are flush ordinarily with the mold cavity. A finished casting may be ejected by force exerted or applied to the underside of the pins at 34 should such action be desired or necessary.

50 The frame 12 at its upper end centrally carries a pneumatic lift cylinder 40 having a piston 42 therein swivelly connected to the spider 44 which supports and carries the upper mold section. Details of the piston and cylinder and swivel connector are immaterial in this modification, but may, if desired, be constructed similar to Fig. 5, hereinafter to be described.

55 60 The spider 44 is provided with an annular rim 46 having an annular shoulder 48 for centering

the mold section 50 which is secured in any suitable manner as by bolts 52 to the rim. In order to steady the shafts supporting the upper and lower mold sections, and guide them into accurate 5 concentric engagement, the lower shaft 16 may be provided on its end with a socket member 54 which is adapted to receive the depending end 56 of the upper shaft 42. An annular shoulder 58 on the socket member may be provided to 10 support and center a flanged diaphragm member such as 60 into which a lining is to be centrifugally cast, the shoulder being so arranged as to 15 secure the diaphragm snugly between the upper inner face 62 of the upper mold and the shoulder 58.

Carried upon the lower shaft 16 is an annular trough 70 constructed preferably of refractory material which, as shown, is independently supported from the shaft in a vertically adjustable 20 manner, free from the mold supports, thereby preventing the trough from overheating due to 25 heat flow from the mold sections. As shown in Figs. 1 and 2, the annular trough is carried upon a spider 72, and is provided with an inner wall 25 having notches 76 adapted to regulate the level of molten metal, or charge, and an outer wall 78 extended to a height sufficient to insure discharge 30 of metal only after considerable rotation speed is attained, so that the metal will impinge upon the metal diaphragm member with considerable force.

In order to provide for suitable expansion of the diaphragm after heat is transferred to it by the cast metal, a small clearance 78 is provided 35 between the flange 80 and the mold surface 82 so that no buckling of the disc portion will take place. The curvature of the corner 84 in the mold is also made of short radius, preferably shorter than the radius of curvature between the flange and disc portion of the diaphragm, so that expansion may take place into the corner if necessary.

To provide a mechanical interlock between the cast metal and shell or diaphragm which will 40 safeguard the composite construction against contraction of the liner away from the shell should the elements be not adequately welded together although such has not been found to occur, the edge of the flange 80 may be bell mouthed as at 84 or otherwise suitably formed 45 and extend into the flange forming annular groove 88, whereby cast metal may completely encircle the flange edge. This construction also aids in the more uniform cooling of the heavy 50 section of the casting since the flange extends substantially into the center thereof.

A particular advantage inherent in the machine is derived from the particular form of the article manufactured thereby. The use of a flange diaphragm tends to protect the upper mold section, thereby permitting the use of a permanent mold material such as steel or a suitable refractory. The lower mold section while not so well protected may be more or less permanent and constructed of steel or any suitable refractory material capable of withstanding the stresses of centrifugal casting. The extreme simplicity of the lower mold section and its simple mounting, it being held in place by the annular shoulder 55 22 and by the weight of the upper mold section permits of quick and cheap replacement as often as necessary without cooling or delaying rapid production. As shown in Fig. 3, the upper mold section 50 may be extended by an annular lip 56 75 having an inner tapered surface 58 against

which a refractory insert 55 may seat. In this particular modification the refractory insert may be of the sand core type because of the support rendered to it by the surrounding mold 50 and lip 56 and rim portion 20.

In Fig. 4, the method of preparing the machine when cold is illustrated. Blocks preferably of refractory material are placed between the upper and lower mold sections and asbestos protection shields are provided at various other 10 points while a heating torch is applied to the mold cavities. As shown, a central block 90, which may be in segmental form for easy placement and removal, guards the inner shaft and support spiders from the torch. A screen 92 15 suitably hung upon the annular trough is adapted to protect the lower mold spider and adjacent parts, while a cylindrical shield 94 is placed around the mold to prevent loss of heat. The shield 94 may be removably supported on brackets 96 in the manner shown. An aperture 98 therein offers access to the interior of the mold and a suitable torch 100 may be inserted therethrough.

A novel diaphragm holding and ejecting means 25 for use in connection with the machine is illustrated in Figs. 4 and 5 wherein channels 110 are shown as terminating in ports 112 in the upper mold face 62. The number of ports may be varied to suit but are preferably arranged at short 30 intervals and all connected to the channel 110. Referring to Fig. 5, the channels 110 enter into an axial bore 113 passing through the shaft 115, which shaft is rotatably carried in the piston 114 and piston rod 116. Raising or lowering of 35 the upper mold section is accomplished by admitting compressed air to the lower part of the cylinder from the supply pipe 117, or exhausting the cylinder into the exhaust connection 118 of the three-way valve 119. Referring again to the 40 ports 112 and connecting channels 110, the upper end of the cylinder may be provided with a three-way valve 120 adapted to connect the upper end 45 of the cylinder either to a source of vacuum 122 or pressure 117. It will thus readily appear that by application of vacuum, a diaphragm such as 60 may be securely held against the under face 62 of the upper mold section by reason of the ports 112, and ejection of the diaphragm may be quickly accomplished by reversing the suction to 50 pressure. Since movement of the piston in and out of the upper portion of the cylinder may seriously affect the vacuum operation, it may be desirable to provide a flexible and swivel hose connection between the upper end of shaft 116 55 and the valve 120 in which case the packing 124 may be dispensed with. However, in practice it has been found that when the piston rises, vacuum used to hold the diaphragm in place is reduced tending to initiate ejection which is desirable at this time. 60

Referring to Fig. 3 wherein the finished brake drum structure is shown, it will appear that the cast metal liner 130 is mechanically interlocked over the bell mouth edge 84 in addition to being substantially welded to the flange 80 of the diaphragm. After casting and cooling, the drum is removed, and the inner skin which includes the impurities may be machined away so as to produce a high grade internal friction braking surface.

In operation of the machine, the same is first heated to the operating temperature, preferably while rotating slowly, in the manner described in connection with Fig. 4, this being done to pre- 75

vent chilling of the first castings made. After heating, the liners 90, 92 and 94 are removed and an amount of molten metal sufficient to fill the annular trough 78 to the overflow point is poured thereinto, any excess overflowing into the catch troughs 73. A flanged diaphragm is inserted in the top mold section and the sections are thereafter brought together by exhausting cylinder 40. Rotation and rapid acceleration is immediately commenced, and after a predetermined speed is attained the metal will flow up over the lip (see Fig. 2) and be discharged with high velocity against the flange 80 heating it to the temperature of the iron and thereafter flow as indicated in Fig. 2 to fill the cavities. The diaphragm when subjected to the heat and impingement expands so as to take up the clearance, and soon after the metal is discharged from the trough, the molds are rapidly decelerated as by reversing the current flow in the motor and supplying a resistance, separated, and the brake drum with its shell and liner both welded and locked removed for uniform normal cooling in atmosphere or in any other desirable medium. Acceleration, the running time, and deceleration, in all may take a fraction of a minute. Also the time during which the molten metal must lie in the trough is extremely short, since the acceleration period is short due to the annular construction of the trough whereby the molten metal is rapidly accelerated therewith. This annular shape thereby greatly prolongs the life of the trough.

There is thus provided an improved article of manufacture and machine adapted to cooperate therewith during the process of manufacture whereby rapid manufacture of brake drums and the like at low cost is possible.

Though only one embodiment or modification of the invention has been illustrated and described, it is to be understood that the invention is not limited thereto but may be embodied in various mechanical forms. For example, the size and proportions may be varied at will to suit various conditions, or the mechanical elements thereof may be varied or equivalent substitutions made therefor. As such and many other changes in construction and arrangement of parts may be made without departing from the spirit of the invention, as will be apparent to those skilled in the art, reference will be had to the appended claims for a definition of the limits of the invention.

What is claimed is:

1. An insert shell for use in casting a brake drum comprising a drum shaped member having an inturned head portion along one edge, and a bell-mouthed portion along the other edge.
2. A rotatable annular trough having an outer annular high lip sloping slightly radially outward toward the top, and an inner lip provided with an overflow discharge means for regulating liquid capacity.
3. A centrifugal casting machine, a two-part rotatable mold, means for rotating one of the parts, means for rotatably supporting and raising and lowering the other of the parts into and out of engagement with the first part, and vacuum and pressure ports leading into said mold cavity for securing or releasing a metallic insert in said cavity by suction or pressure thereon.
4. In a centrifugal casting machine, a two-

part rotatable mold, means for raising or lowering one of the parts and for rotatably supporting the same, ports on the inner surface of said mold, and means including a controlling valve for connecting said ports to a source of fluid 5 vacuum or pressure at will to hold or release a metallic insert adapted to seat over said ports.

5. In a centrifugal casting machine a two-part annular mold, means for rotating and supporting one of the parts upon a vertical axis, and 10 an annular pouring trough within said mold independently supported and spaced therefrom and adapted for rotation with a part of the rotatable mold.

6. In a centrifugal casting machine, a two-part 15 annular mold, means for rotating and supporting one of the parts upon a vertical axis, a flanged diaphragm adapted to seat in said mold, means adapted to hold said flanged diaphragm in the other of said parts, and an annular 20 trough within said mold removably supported for rotation with and spaced from the rotatable part, said annular trough being adapted to discharge metal upon the flange of said flanged diaphragm during rotation. 25

7. A rotatable vertical axis annular trough, an annular mold around said trough, spaced supporting means for the mold underneath said trough and discharge means in said trough for regulating the liquid level, said discharge means 30 being located so as to discharge between the spaced supporting means.

8. In a vertical axis centrifugal casting machine, an upper mold section, a lower mold section, said upper mold section having an annular 35 groove facing and partially bounded by the lower mold member, and a removable refractory insert arranged in said groove.

9. In a vertical axis centrifugal casting machine, an upper mold section having an annular 40 groove in the inner lower edge thereof, a refractory insert removably arranged in said groove, a lower mold member adapted to engage the lower edge of said upper mold section and refractory insert and retain the refractory insert 45 in place, and a flanged diaphragm member covering the inner exposed surface of said upper mold section and extending over and adjacent to a portion of the exposed surface of said refractory insert. 50

10. A centrifugal casting machine, a two-part rotatable mold, means for rotating one of the parts, means for rotatably supporting and raising and lowering the other of the parts into and out of engagement with the first part, and vacuum ports leading into said mold cavity in a direction substantially parallel with the rotational axis for securing a metallic insert having an inturned head portion in said cavity by suction on the insert head portion. 55

11. A centrifugal casting machine, a two-part rotatable mold, means for rotating one part of said mold, means for rotatably supporting and raising and lowering the other part of said mold into and out of engagement with the first part, and means movable with one of said parts for centering and securing a metallic insert in the mold, and means on the other of said parts for securing the metallic insert in the mold, independent of said movable means. 60 70
